UNITED STATES PATENT OFFICE.

EDWARD KELLY AND EARL REYNOLDS, OF BRADLEY BEACH, NEW JERSEY, ASSIGNEES
OF ONE-FIFTH TO FREDERICK NEWMAN, OF MANASQUAN, NEW JERSEY.

VAPORIZER FOR GAS-ENGINES.

1,222,106.

Specification of Letters Patent. Patented Apr. 10, 1917.

Application filed April 1, 1916. Serial No. 88,407.

To all whom it may concern:

Be it known that we, EDWARD KELLY and EARL REYNOLDS, citizens of the United States, residing at Bradley Beach, in the 5 county of Monmouth and State of New Jersey, have invented certain new and useful Improvements in Vaporizers for Gas-Engines, of which the following is a specification.

10 Our invention relates to new and useful improvements in vaporizers or carbureting devices, the primary object of our invention being the provision of means whereby the ordinary gasoline tank of a motor vehicle 15 may be utilized as a carbureter for mixing the gasoline with suitable quantities of air before supplying it to the engine.

A still further object of our invention consists in constructing the gasoline tank in 20 two independent gasoline holding compartments which may be filled to a certain predetermined level and which, at a point above this level, communicate with each other and with a fuel mixture or carbureted air chamber or compartment from which a supply pipe leads to a carbureter.

A still further object of our invention consists in the provision of means whereby air may be supplied to each or both of the gasoline holding tanks at a level below the gasoline contained therein in order that the suction in the tank created by the movement of the pistons in the engine cylinders may draw the air so supplied through the gasoline to 35 vaporize the gasoline.

In this connection, a still further object of our invention consists in the provision of a suitable check valve in the pipe supplying the explosive mixture to the engine to prevent danger of explosions in the tank, due to 40 back firing and to provide a safety valve to prevent bursting of the pipe between the engine and check valve in case of back firing.

45 A still further object of our invention consists in providing a supplemental fuel tank of relatively small capacity which may be mounted within the hood of the vehicle and from which gasoline may be supplied 50 directly to the pipe leading to the engine manifold for the purpose of priming the engine, a suitable form of valve being furnished to control the supply of priming fuel.

55 With these and other objects in view, our

invention will be more fully described, illustrated in the accompanying drawings, and then specifically pointed out in the claim which is attached to and forms a part of this application.

60

In the drawings:

Figure 1 is a central vertical longitudinal sectional view of our invention;

Fig. 2 is a horizontal sectional view on the line 2-2 of Fig. 1, looking in the direction of the arrows;

Fig. 3 is a transverse sectional view on the line 3-3 of Fig. 1, also looking in the direction of the arrows;

Fig. 4 is an elevational view, partially in section, of the valve casing employed in connecting the fuel outlet pipe with the manifold of the engine, illustrating the safety valve and throttle valve;

Fig. 5 is a longitudinal sectional view of the valve controlling the supply of gasoline from the supplemental fuel tank to the fuel supply pipe;

Fig. 6 is a fragmentary section, upon an enlarged scale, of the suction head through which the explosive mixture is drawn to the engine.

Corresponding and like parts are referred to in the following description and indicated in all the views of the drawings by the same reference characters.

Our invention includes a main fuel tank or reservoir 10, preferably constructed of sheet metal in the usual manner and either rectangular or cylindrical in shape, as preferred. This tank is divided into spaced fuel chambers 11 and 12 separated by a fuel mixture chamber 13 by means of the spaced vertical transverse walls 14 and 15. As shown in Fig. 3 of the drawings, these walls, adjacent the top of the tank, are formed with openings 16 by means of which communication is established between the chambers 11, 12 and 13. The end walls of the tank are formed with filling spouts 17 through which the fuel chambers 11 and 12 may be filled and in which fuel will appear before the fuel level in such chambers reaches the openings 16 in the partition walls so that filling of the chamber 13 may be avoided, 95 these spouts being normally closed by threaded caps 18. The bottom of the tank is preferably provided with drain cocks 19 communicating one with each of the fuel chambers 11 and 12 in order that any water 100

110

or other impurities accumulating in these chambers may be withdrawn from time to time.

Pipes 20 and 21 extend downwardly through the top wall of the tank 10 into the chambers 11 and 12 and, at their lower ends, carry hollow disk-shaped nozzles 22 which are supported by the pipes in slightly spaced relation above the bottom of the tank. These nozzles, in their upper and lower faces, are formed with a plurality of openings 23 by means of which air drawn through the pipes 20 may escape from the nozzles and pass upwardly through the gasoline contained in the chambers 11 and 12. Each of the pipes 20 and 21 is provided with any suitable form of manually operable cut-off valve 24 and an air supply pipe 25 is connected at one end to the pipe 20, forming a continuation of this pipe and is also connected at a point within its length with the pipe 21. This pipe 25, at its free end, opens into a funnel-shaped member 26 forming the air intake of the vaporizer. This member 26 may be disposed with its flared open end adjacent the exhaust manifold of the engine or in communication with a heating jacket, as preferred, in order that the air supplied through the pipe 25 may be heated.

The top wall of the tank 10 is formed with an opening 27 to receive a suction head 28 which extends into the fuel mixture chamber 13 of the tank. This suction head is preferably in the form of a sphere having a circular series of openings 29 formed in it immediately within the tank and carrying, below this series of openings, a concavo-convex baffle plate or deflector 30 disposed with its concave face outermost and acting to prevent splashing of fuel into the suction head and to cause a uniform drawing of vapor from all of the chambers into the head. A pipe 31 leads from this suction head to a valve casing 32 having a flange 33 adapted for connection to the corresponding flange of the intake manifold, not shown, of an engine.

This valve casing 32 is substantially L-shaped, the flange 33 being formed at the free terminal of one arm and the pipe 31 being connected to the free terminal of the other arm. This second arm is enlarged intermediate its length to form a chamber 34 inclosing a check valve 35 which may open through suction of the engine cylinders to permit passage of a combustible mixture from the pipe 31 to the cylinders, but which will automatically close to prevent any return passage of the mixture and, consequently, to protect the tank and its contents against back firing of the engine. The other arm of the valve casing is provided with the usual throttle valve 36 of the butterfly type and such arm, at its point of juncture

with the check valve carrying arm, is preferably formed with a cylindrical extension providing a valve chamber 37. This valve chamber communicates directly with the atmosphere and incloses a valve seat 38 and co-acting check valve 39 normally held to its seat by a spring 40 engaging between the check valve and a flange 41 formed interiorly of the open end of the chamber 37. Obviously, in case of back firing, the burning gases from the engine cylinders, if they pass the intake valves of the cylinders, may escape from the valve casing 32 by passing through the valve 39 and all danger of bursting either the intake manifold of the engine or the valve casing 32 is, therefore, avoided.

Although the above described structure comprehends all the vital features of our invention, we preferably make a special provision for priming the engine cylinders. To accomplish this, we provide a supplemental fuel tank 42 of relatively small size which may be secured to the dash 43 of the vehicle within the hood or at any suitable point at a level above the valve casing 32 and which is formed with a filling opening normally closed by a cap 44. A pipe 45 leads from the bottom of this supplemental tank 42 to a cylindrical valve casing 46 and a pipe 47 leads from the outer end of this valve casing to the pipe 31 at a point adjacent the valve casing 32. The valve casing 46 is provided with a valve seat 48 located in that end of the casing communicating with the pipe 47 and adapted to coöperate with a needle valve 49, the stem 50 of which is threaded through the opposite end of the valve casing 46 and provided with a handle 51 by means of which the valve may be opened or closed.

With the above described vaporizer, when the vehicle is to be started, one or both of the valves 24 is opened, the valve 49 is opened to such an extent as to permit a predetermined flow of pure gasoline to the pipe 31, the throttle valve 36 is opened in the same manner in which the ordinary throttle valve of a carburetor is opened, and the engine is started either by hand or by any suitable form of starting mechanism. During the early part of the running of the engine, the explosive mixture is formed by air drawn into the main tank through the pipe 25 and pipes 20 and 21 and from such tank through the pipe 31 and valve casing 32 to the engine manifold, this air meeting the pure gasoline entering the pipe 31 from the pipe 47 and mixing with it. After the engine has been running for a short time, the air admitted to the tank 10 will be heated and will take up gasoline during its passage through the chambers 11 and 12 and thus form an explosive mixture within the tank 10, which is drawn through the pipe 31 to the engine. As the air becomes sufficiently heated, this mixture will

become rich enough to form a suitable fuel for the engine, after which the valve 49 may be closed and all fuel drawn directly from the tank 10. As previously pointed out, the 5 check valve 36 and safety valve 39 serve to protect the vaporizer in case of back firing of the engine. Preferably, the suction head 28 is provided with a transverse strainer 52 which extends transversely of the head be- 10 tween the intake openings 29 and the pipe 31 to prevent the passage of impurities to the engine.

It should be noted that the heated air continually passing through the liquid fuel contained in the fuel chambers heats the fuel to a considerable extent and inasmuch as one of these chambers is disposed at either side of the vapor chamber, it will be clear that all fuel mixture generated in this chamber 20 is kept heated until it is drawn into the engine.

Although we have illustrated and de- scribed our invention in all its details of construction, it will of course be under- 25 stood that we do not wish to limit ourselves to such details, as various minor changes, within the scope of the appended claim

may be made at any time without in the slightest degree departing from the spirit of our invention.

30

Having thus described the invention, what is claimed as new is:

A vaporizer for internal combustion engines including a tank divided into fuel and fuel mixture chambers in communication 35 with each other, an air supply pipe extending into the fuel chamber and below the liquid level therein, a suction head extending into the fuel mixture chamber of the tank, and a pipe leading from the suction 40 head to supply the fuel mixture to the engine, the suction head being substantially spherical in shape and formed with a series of encircling openings, a concavo-convex baffle member secured to the head below the 45 openings with its concave face directed downwardly, and a strainer across the head between its openings and the pipe connected thereto.

In testimony whereof we affix our signatures. 50

EDWARD KELLY. [L. S.]
EARL REYNOLDS. [L. S.]
